DESIGN FOR A BICYCLE STEERING POST

Ewald F. Pawsat, Maysville, Ky.

Application January 16, 1946, Serial No. 125,619

Term of patent 14 years

(Cl. D90—11)

To all whom it may concern:

Be it known that I, Ewald F. Pawsat, a citizen of the United States of America, residing at Maysville, in the county of Mason, State of Kentucky, have invented a new, original, and ornamental Design for a Bicycle Steering Post, of which the following is a specification, reference being had to the accompanying drawing, forming part thereof.

Fig. 1 is a perspective view of a bicycle steering post showing my new design.

Fig. 2 is a top plan view of the same.

Fig. 3 is a front elevational view thereof.

I claim:

The ornamental design for a bicycle steering post, as shown.

EWALD F. PAWSAT.
